UNITED STATES PATENT OFFICE.

EDWARD L. GAYLORD, OF BRIDGEPORT, CONNECTICUT.

FOLDING CHAIR.

SPECIFICATION forming part of Letters Patent No. 357,591, dated February 15, 1887.

Application filed February 25, 1886. Serial No. 193,169. (No model.)

To all whom it may concern:

Be it known that I, EDWARD L. GAYLORD, a citizen of the United States, residing at Bridgeport, in the county of Fairfield and State of Connecticut, have invented certain new and useful Improvements in Folding Chairs; and I do hereby declare the following to be a full, clear, and exact description of the invention, such as will enable others skilled in the art to 10 which it appertains to make and use the same.

My invention relates to certain new and useful improvements in folding chairs, and especially to that class shown in my Letters Patent Nos. 330,222, 330,223, 330,224, and 330,225, and 15 has for its object to still further simplify and improve the construction shown in said patents; and with these ends in view my present invention consists in the details of construction and combination of elements hereinafter explained, and then specifically designated by the 20 claims.

In order that those skilled in the art to which my invention appertains may fully understand its construction and operation, I will proceed 25 to describe the same in detail, referring by letter to the accompanying drawings, forming a part of this specification, in which—

Figure 1 is a side elevation of a portion of a chair-standard and chair embodying my present improvement; Fig. 2, a vertical section of the standard, showing the operative parts in elevation; Fig. 3, an inverted detail perspective of the chair seat and frame in their relative position, a portion of the latter being broken away; 30 Fig. 4, a section at the line $x-x$ of Fig. 1; and Fig. 5 is a perspective view of sufficient of my above-named patented improvement to illustrate my present invention applied thereto, the parts being shown in full lines in the position of 35 use and in dotted lines in position when the foot-rest is turned up out of the way.

Similar letters denote like parts in the several figures of the drawings.

In practice it has been found desirable when 45 chairs are to be used in public halls to have a foot-rest; but where the chair folds upon itself, so as to afford an unobstructed exit in case of fire or accident, it has been found difficult to provide such a rest. These difficulties I over 50 come in the following manner:

To the rear of the standard A is pivoted the

foot-rest B, the short end of which extends inward and is provided with a pin, C, projecting forward, for the purpose presently explained. Within the standard is pivoted the 55 seat-frame D, in the same vertical plane as is the foot-rest. This frame extends inward from its pivotal point and has projecting from its rear a pin, E, in vertical alignment with the pin C. A rod, F, connects these two pins, so that any 60 movement of the seat-frame about its pivotal point will cause the foot-rest to have a like movement about its pivotal point, and vice versa. Thus it will be seen that when the chair is open for use a foot-rest is afforded the person 65 occupying the chair next in the rear; but when the seat-frame is folded the rest is also simultaneously folded, and as it is pivoted outside of the frame and in the same vertical plane it will take the position shown in dotted lines in Fig. 70 1, where it will be entirely out of the way.

G is a rod secured to the standard by bolts, and H is a coil-spring placed upon said rod, its free end adapted to bear upon the pin C, the tendency of which is to force the inner end of 75 the rest and seat-frame downward.

I is a ratchet placed upon the rod G and having a shank, to which one end of the spring H is attached. By operating the ratchet more or less tension may be given to the spring, so as to 80 overcome the weight of the seat-frame and rest.

Cast with or secured to the ends of the seat-frame and projecting inward therefrom are open lugs or sockets J. Secured to the under side of the seat K are fork-like hooks L, which 85 pass within the openings in the lugs, thus forming a hinge joint or connection between the seat and the frame. To remove the seat it is only necessary to turn it to an upright position, when the hooks may be readily withdrawn from 90 the openings in the lugs.

While the seat may be readily removed when desired, there is no liability of accidental displacement, from the fact that the heels of the hooks, when the seat is in position for use, abut 95 against the lugs, thus preventing the withdrawal of said hooks. This feature of my improvement is of great importance, as it greatly facilitates the shipment and repairing or cleaning of the chairs, and also makes the seats interchangeable, so that the chairs may be provided in the winter with upholstered seats and 100

in the summer with perforated or cane seats, and this will be readily seen to be a great advantage.

Of course I do not limit myself to the style of standard or frame shown, as this is a matter of convenience or taste, for my foot-rest may with equal facility be applied to any of the constructions shown in the patents above referred to; also, my manner of detachably pivoting seats to chairs may be used in connection with any form of chair without departing from the spirit of my invention.

Having thus described my invention, what I claim as new and useful is—

15 1. The herein-described combination of the seat-frame and foot-rest, pivoted in the same vertical plane and connected by a rod or link,

and a spring adapted to close or fold said frame and rest, as shown and specified.

2. In a folding chair, the combination, with the seat-frame adapted to swing inwardly and laterally, of a foot-rest pivoted to the rear of the standard of the chair, and a link connected to said frame and rest at their inner extremities, whereby a simultaneity of movement is had between said frame and seat, substantially as shown and set forth.

In testimony whereof I affix my signature in presence of two witnesses.

EDWARD L. GAYLORD.
